CLAIM

The ornamental design for a support strut for a modular workspace system, as shown and described.

DESCRIPTION

FIG. 1 is a front view of a support strut for a modular workspace system showing my design;

FIG. 2 is a bottom plan view;

FIG. 3 is a side elevational view, the opposite side being a mirror image thereof; and

FIG. 4 is a rear view.

The work surface shown by means of dotted lines is for illustrative purposes only.

FIG. 1.

FIG. 3.

FIG. 2.

FIG. 4.
